FIG. 3

FIG. 2

FIG. 1

FIG. 1 is a front elevational view of trousers embodying my new design.

FIG. 2 is a side elevational view thereof.

FIG. 3 is a rear elevational view thereof.

The characteristic features of my design reside in the combination on the trousers disclosed, of a wide split yoke portion, which extends from points back of the side median lines of the trousers, around to the front median line, where the ends of the yoke overlap and are secured together by fasteners, all as shown.

I claim:

The ornamental design for trousers, as shown and described.
